CLAIM

The ornamental design for a garment, as shown and described.

DESCRIPTION

FIG. 1 is a front left perspective view of a garment showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The evenly spaced broken lines depict stitching which forms part of the claimed design. The dash-dot-dash broken lines on the garment depict portions of the garment that form no part of the claimed design. The dash-dot-dash broken lines that outline the partial human figure assists in illustrating how the garment may appear when in a position of use and forms no part of the claimed design. The dash-dot-dot-dash broken lines are boundary lines that form no part of the claimed design.
